ADJUSTABLE COLUMN MAGNIFIER

George O. Bosma, Denver, Colo., assignor to LRI Corporation, Denver, Colo., a corporation of Colorado

Filed Dec. 4, 1968, Ser. No. 14,784

Term of patent 14 years

Int. Cl. D16—08

U.S. Cl. D57—1

FIG 5

FIGURE 1 is a front elevation of an adjustable column magnifier showing my new design;

FIGURE 2 is a right side elevation with portions broken away for ease of illustration;

FIGURE 3 is a rear elevation view thereof;

FIGURE 4 is a bottom plan view taken at an enlarged scale; and

FIGURE 5 is a perspective view as seen from the top and to the right of the present FIGURE 1.

The undisclosed left side is a mirror image of the right side.

I claim:

The ornamental design for an adjustable column magnifier, as shown and described.
